UNITED STATES PATENT OFFICE

102,876

DESIGN FOR A BOWL OR SIMILAR ARTICLE

Maurice Exelmans, Paris, France, assignor to Verlys of America, Inc., New York, N. Y., a corporation of New York

Application June 18, 1936, Serial No. 63,367
In France February 21, 1936

Term of patent 7 years

To all whom it may concern:

Be it known that I, Maurice Exelmans, a citizen of the Republic of France, and a resident of Paris, France, have invented a new, original, and ornamental Design for a Bowl or Similar Article, of which the following is a specification, reference being had to the accompanying drawing, forming a part thereof.

Fig. 1 is a top perspective view of the bowl or similar article, showing my design, and
Fig. 2 is a bottom plan view thereof.

I claim:

The ornamental design for a bowl or similar article, as shown.

MAURICE EXELMANS.
